UNITED STATES PATENT OFFICE.

L. H. OLMSTED, OF NEWARK, NEW JERSEY.

IMPROVEMENT IN OIL-CANS.

Specification forming part of Letters Patent No. 42,593, dated May 3, 1864.

To all whom it may concern:

Be it known that I, LEVERETT H. OLMSTED, of the city of Newark, in the county of Essex and State of New Jersey, have invented certain Improvements in Oilers; and I do hereby declare the following to be a full and exact description thereof, reference being herein had to the drawing accompanying this specification, and which makes part of the same.

The nature of my improvement consists in attaching to the tube of the oiler a collar as a place for the fingers in causing the needed pressure to expel the oil; also, in giving a raised and rounded form to the elastic top in its center, where it is attached to the tube.

In the drawing, A is the semi-spherical body of the oiler. B is the elastic top; C, the finger-collar; D, the raised and rounded part of the top, and E the tube. The semi-spherical bottom is counterbalanced by a weight, *a*, (shown by the dotted lines in the drawing,) by which the oiler, when thrown over, is again

restored to an upright position. The rounded and raised center D allows of a strong hold of the tube E, and when raised high enough to allow of a rounded inside beneath the screw of the tube E it gives more freedom to the flow of the oil. The collar C brings the pressure from the fingers more central upon the elastic top B than can be without it, and makes the oiler more convenient for use.

What I claim as my improvement, and desire to secure, is—

1. The attachment of a collar to the tube, for the purpose specified.
2. Combining a raised and rounded top with a semi-spherical bottom, as shown and described.
3. Combining the semi-spherical bottom and weight with the flexible top, as shown.

L. H. OLMSTED.
